Primary Examiner — Paula Allen Greene*(74) Attorney, Agent, or Firm* — WCF IP(57) **CLAIM**

The ornamental design for a microphone holder, as shown and described.

DESCRIPTION

FIG. 1 is a rear, bottom, left side perspective view of a microphone holder, showing the new design;

FIG. 2 is a front, top, right side perspective view thereof;

FIG. 3 is a bottom plan view thereof;

FIG. 4 is a top plan view thereof;

FIG. 5 is a left side view thereof;

FIG. 6 is a right side view thereof;

FIG. 7 is a rear view thereof;

FIG. 8 is front view thereof; and,

FIG. 9 is a front view thereof.

The broken lines in FIG. 9 depict environment structure that forms no part of the claimed design.
